UNITED STATES PATENT OFFICE.

THOMAS P. GREGER, OF PHILADELPHIA, PENNSYLVANIA, ASSIGNOR TO THE GREGER MANUFACTURING COMPANY, OF CAMDEN, NEW JERSEY.

MANHOLE FRAME AND COVER.

SPECIFICATION forming part of Letters Patent No. 636,201, dated October 31, 1899.

Application filed May 4, 1899. Serial No. 715,534. (No model.)

To all whom it may concern:

Be it known that I, THOMAS P. GREGER, a citizen of the United States, residing at the city of Philadelphia, in the county of Philadelphia and State of Pennsylvania, have invented certain new and useful Improvements 5 in Manhole Frames and Covers, of which the following is a specification.

My invention has relation to a manhole 10 frame and cover, and in such connection it relates to the construction and arrangement of the frame and cover.

The principal object of my invention is to provide a manhole frame and cover of simple 15 construction, the frame and cover being so constructed and arranged as to admit of the change from a non-ventilating to a ventilating frame and cover or vice versa.

My invention, stated in general terms, consists of a manhole cover and frame constructed and arranged in substantially the manner hereinafter described and claimed.

The nature and scope of my invention will be more fully understood from the following 25 description, taken in connection with the accompanying drawings, forming part hereof, in which—

Figure 1 is a top or plan view of a frame and cover embodying main features of my 30 invention, the cover being seated in the frame to form a non-ventilating frame and cover. Fig. 2 is a vertical sectional view on the line $x-x$ of Fig. 1. Fig. 3 is a similar view to that of Fig. 1, but with the cover shifted on its 35 seat to form, with the frame, a ventilating cover and frame for the manhole; and Fig. 4 is a vertical sectional view on the line $y-y$ of Fig. 3.

Referring to the drawings, a represents the 40 base of the frame, from which projects the upwardly-extending wall b , having in its interior the flange d , forming the seat for the cover e and extending under the base of said cover. The flange d is cut out at regular 45 points d' to form semicircular and vertical recesses or openings in the seat or flange d . The periphery or rim of the cover e is also cut out so as to form oppositely-arranged semicircular recesses e' , so that when required the 50 cover e may rest on the seat or flange d , with the recesses or openings e' registering with

the recesses or openings d' of the seat d , as illustrated in Figs. 3 and 4. When, however, the cover is shifted slightly on its seat, the openings e' of the cover may be shifted to 55 come opposite the uncut portions of the flange or seat d , the cut-out portions d' of said flange or seat d at the same time resting beneath the uncut portions of the rim of the cover e . The recesses e' extend obliquely along the rim of 60 the cover.

To lock the cover in the frame and to prevent its accidental displacement on the seat d , as well as to serve as a guide in the turning of the cover on its seat, the inner periphery of the wall b is cut out or notched, as at $b' b''$, in the upper edge or rim of the said wall, and into one of these notches a lug or projection e^2 on the rim of the cover is adapted to engage. Thus, as illustrated in Figs. 1 and 70 65 2, the projection e^2 fits into the notch b' and locks the cover so that the openings $d' e'$ are closed, while in Figs. 3 and 4 the lug or projection e^2 fits into the notch b'' and locks the cover so that the openings d' and e' register. 75

The cover may be provided with hand lifts or rings f or other somewhat similar devices, whereby it may be easily and quickly removed from the frame for the purpose of adjustment or otherwise. 80

The cutting out of the rim of the cover e into semicircular recesses e' , oppositely curved with respect to the recesses d' of the ledge d , insures the complete covering of the base of said recesses e' by the uncut portions of said 85 ledge, which portions are corresponding in shape, but larger than the recesses e' . The construction and arrangement above described permits of the cutting out of both the rim of the cover as well as the ledge d without impairing the strength of either the ledge or the cover. 90

Having thus described the nature and object of my invention, what I claim as new, and desire to secure by Letters Patent, is— 95

1. The combination with a frame having an upwardly-projecting wall, an annular flange or ledge formed on the interior of said wall, said ledge being provided with alternate recesses and projections, of a cover, the base whereof 100 is adapted to rest upon the flange or ledge and having its rim provided at intervals with

recesses reversely arranged to the recesses in said ledge, said cover adapted to be supported on said ledge so that its recesses may register alternately with the recesses or projections 5 of the ledge, substantially as and for the purposes described.

2. The combination of a frame having an upwardly-projecting wall, an annular flange or ledge formed on the interior of said wall, 10 said ledge being provided with alternate vertically-arranged recesses and projections, a cover, the base of which is adapted to rest on said ledge and having its rim provided with

obliquely-arranged recesses reversely arranged with respect to the recesses of the ledge, and 15 means for locking the cover within the frame to prevent the turning of the cover on said ledge, substantially as and for the purposes described.

In testimony whereof I have hereunto set 20 my signature in the presence of two subscribing witnesses.

THOMAS P. GREGER.
